(57) **CLAIM**

The ornamental design for a rotomolded water tank as shown and described.

DESCRIPTION

FIG. 1 is a front elevational view of a rotomolded water tank showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a bottom, front and right side perspective view thereof;

FIG. 8 is a top, rear and left side perspective view thereof;

FIG. 9 is an enlarged view of portion 9 in FIG. 1;

FIG. 10 is an enlarged view of portion 10 in FIG. 7; and,

FIG. 11 is a bottom, front and left side perspective view showing the rotomolded water tank in a state of use.

The evenly dashed broken lines in the drawings illustrate portions of the rotomolded water tank which form no part of the claimed design.

The unevenly dashed broken lines illustrate the boundary of the enlarged views and form no part of the claimed design.

1 Claim, 11 Drawing Sheets
